UNITED STATES PATENT OFFICE.

WILLIAM HENDRICK, OF NEW HAVEN, CONNECTICUT, ASSIGNOR TO CHARLES GAY, OF NEW HAVEN, CONNECTICUT.

CHAPLET AND SHRINE OF THE HOLY ROSARY.

No. 899,977.

Specification of Letters Patent. Patented Sept. 29, 1908.

Application filed August 1, 1906. Serial No. 328,720.

To all whom it may concern:

Be it known that I, WILLIAM HENDRICK, a citizen of the United States, and a resident of New Haven, in the county of New Haven and State of Connecticut, have invented a new and Improved Chaplet and Shrine of the Holy Rosary, of which the following is a full, clear, and exact description.

The object of the invention is to provide a new and improved chaplet and shrine of the holy rosary, arranged to successively display pictures of a religious character, one at a time and in proper order, according to the intended devotional exercise.

The invention consists in novel features and parts and combinations of the same, which will be more fully described hereinafter and then pointed out in the claim.

A practical embodiment of the invention is represented in the accompanying drawings forming a part of this specification, in which similar characters of reference indicate corresponding parts in all the views.

Figure 1 is a perspective view of the improvement; Fig. 2 is a sectional rear elevation of the same on the line 2-2 of Fig. 3, and Fig. 3 is a transverse section of the same on the line 3-3 of Fig. 2.

The casing A, adapted to be fastened on a wall or placed on a table or other support, is provided with a display front A' having an opening A² preferably covered with a pane B of glass or other transparent or translucent material. An endless web C of paper or other flexible material and containing pictures or the like on its outer face is adapted to move in a stretched condition past the rear face of the pane B, to display the pictures in the opening A², the pictures being preferably of a religious character and of a size for one to fill the opening A² at a time, and the said pictures are arranged in a predetermined order and successively displayed in the opening A² according to the intended devotional exercise. The portion of the web C not stretched over the pane B is arranged in folds within the casing A, and in order to move the web C, to hold a portion C' stretched in the rear of the pane B and to fold the remaining portion C² within the casing A, the following device is provided: The stretched portion C' of the web C extends over the front of a board D held within the casing A and spaced from the pane B, and the upper end of the stretched portion C' passes be-

tween the drawing rollers E and F, of which the drawing roller E is journaled in suitable bearings in the upper portion of the casing A, and the drawing roller F is journaled on a spring frame F' attached to the casing and serving to exert sufficient pressure on the web C to draw the latter along when the roller E is rotated.

As indicated in Fig. 3 the front of the roller E is approximately flush with the front face of the board D, so that the web C readily passes up over the roller E and then between the rollers E and F, continued adhesion of the web C to the roller E being prevented by fingers D' preferably formed integrally on the upper end of the board D and engaging the inner face of the web C at cut-out annular portions E' in the roller E. The web C as it leaves the drawing rollers E and F passes into the folding space A³ formed within the casing A, and having side walls D² secured to the board D, as plainly indicated in Fig. 2. In order to form the folds spring arms G are provided secured to the upper end of the casing A, and located approximately opposite the fingers D' to engage the outer face of the web C, the said spring arms being curved, as shown in Fig. 3, to insure a ready formation of the folds. The lowermost folds are engaged by a retarding device in the form of a cross bar H, secured to the side walls D² adjacent to a guide I, extending on the rear face of the board D and secured to the side walls D². Thus a narrow slit or space is provided between the guide I and the retarding device H, for the web C to pass from the folding space A³ over the guide I and then over another guide D³, formed integrally on the lower end of the board D and leading to the front face thereof a distance below the bottom of the display opening A².

In order to hold the web C in proper side-wise alinement, edge guides J are provided, secured to the inner faces of the side walls D² at the guides I and D³; and in order to give the desired tension to the web C to hold the portion C' in a proper stretched condition, a tension arm K is provided, secured to the bottom of the casing A and extending to and frictionally engaging the outer face of the web C at the lower portion of the guide D³, as will be readily understood by reference to Figs. 2 and 3.

Any desired mechanism may be employed

for turning the drawing roller E with a view to move the web C intermittently past the display opening A²; for instance, a crank arm L may be connected with the shaft of the roller E, to enable the operator to turn the drawing roller in the proper direction.

By the arrangement described an exceedingly long, endless web C, containing many pictures, may be employed, as the web readily 10 folds into a comparatively small space and only the portion displayed at a time is held in a stretched condition in the display-opening A².

By using an endless web in the manner 15 described no rewinding of the web is required, and consequently the web is always in proper position, and it is only necessary to turn the drawing roller E in one direction to successively display the pictures in the 20 display-opening A².

The apparatus shown and described is very simple and durable in construction and is not liable to easily get out of order.

Having thus described my invention, I claim as new and desire to secure by Letters Patent:

An apparatus of the class described, comprising a casing having a display opening, an endless web arranged within the casing and having a portion extending behind the display opening, feed rollers at the upper end of the display opening between which the web passes, guides fixed in the casing at the lower end of the display opening, and over which said web passes, a retarding device comprising a crossbar within the casing adjacent to the guides for supporting the web and guides for the edges of the web adjacent to said first named guides.

In testimony whereof I have signed my name to this specification in the presence of two subscribing witnesses.

WILLIAM HENDRICK.
